UNITED STATES PATENT OFFICE

2,447,291

THREAD SEPARATOR FOR WEFT
REPLENISHING LOOMS

Richard G. Turner, Worcester, Mass., assignor to
Crompton & Knowles Loom Works, Worcester,
Mass., a corporation of Massachusetts

Application February 15, 1946, Serial No. 647,954

6 Claims. (Cl. 139—247)

1

This invention relates to improvements in weft replenishing looms and it is the general object of the invention to provide improved and simple means for separating the weft ends extending from a reserve bobbin magazine.

When a pneumatic thread holder is used with a magazine having several stacks of bobbins wound with coarse yarn difficulty is sometimes experienced in getting the weft ends into the intake mouth due to the fact that the yarns cling together. This condition exists not only at the intake mouth, but also in the several groups of threads leading from the magazine to the holder. It is an important object of my present invention to provide the magazine with a thread separator which will hold the weft ends of the several stacks of bobbins in separated relation, thereby preventing entanglement of the several groups of threads.

In a type of stationary magazine which has gone into general use the outside or end plate of the magazine guides the tips of two pairs of stacks of bobbins, and a thread slot is provided in the end plate for each pair of stacks. The thread slots are necessarily narrow and because of this fact the two groups interfere with each other, particularly if the shuttle corresponding to one group is more active than the shuttle for the other group. It is another object of my present invention to provide a thread separator extending along the thread slot and so constructed as to cause a wide spacing of the weft ends of the two corresponding stacks of bobbins.

It is another object of the invention to make the intake mouth of the thread holder of such shape that the groups of weft ends leading from the separators will enter the mouth at different points, thereby avoiding interference of the threads of each group with respect to the threads of the other groups. This feature of the invention is effected by the use of some such means as a baffle plate within the thread holder toward which all the weft ends converge, the baffle being spaced far enough from the intake mouth beyond the magazine to permit the groups of weft ends to occupy their own zones along the length of the intake mouth.

With these and other objects in view which will appear as the description proceeds, my invention resides in the combination of arrangement of parts hereinafter described and set forth.

In the accompanying drawings, wherein a convenient embodiment of my invention is set forth,

Fig. 1 is a side elevation of part of the loom

having my invention applied thereto, parts being in section.

Fig. 2 is an enlarged horizontal section on line 2—2 of Fig. 1.

Fig. 3 is an enlarged front elevation, parts being in section, looking in the direction of arrow 3, Fig. 1.

Fig. 4 is a detailed view of one of the separators looking in the direction of arrow 4, Fig. 3 and showing the support therefor in section.

Fig. 5 is a side elevation of the thread holder on an enlarged scale, looking in the direction of arrow 5, Fig. 3, and

Fig. 6 is a horizontal section on line 6—6, Fig. 5.

Referring particularly to Figs. 1 and 2, the loom frame 10 supports a magazine M of the multicolor type provided with four groups of reverse bobbins designated in Fig. 2 at I, II, III and IV. The magazine has an outside or end plate 11 formed with a bobbin tip guideway 12 for each stack of bobbins. The plate 11 is provided with two thread slots the forward of which indicated at 13 corresponds to the front pair of stacks I and II, and the rear of which indicated at 14 corresponds to the back pair of stacks III and IV.

Weft ends extend from the bobbins through their respective thread slots, the weft ends W1 and W2 for the front pair of stacks passing through slot 13 in a direction away from the loom, while weft ends W3 and W4 extend similarly through the rear thread slot 14. As successive transfer operations occur the bobbins descend toward a common central transfer position in the usual manner.

The upper part of frame 11 is provided with two horizontal bobbin slots 15 and 16 corresponding respectively to the front and back pairs of bobbin stacks, and front and back vertical rods 17 and 18 are secured at their upper ends to the end frame 11 and extend downwardly across their bobbin slots and are spaced a short distance from and substantially parallel to their corresponding thread slots. When bobbins are placed in the magazine they are inserted butt end first through one or the other of the horizontal bobbin slots 15 or 16 and their weft ends are drawn outwardly away from the loom in the general manner suggested in Figs. 2 and 3.

The pneumatic thread holder to be described in detail hereinafter is supplied with a partial vacuum by means of an air pump 20 fixed to the loom frame and having a piston 21 operated by a lever 22 connected by rod 23 to the lay L of the loom. As the lay reciprocates backwardly and

forwardly the lever 22 causes movement of the piston, and the pump is so constructed that on backward movement of the lay a partial vacuum is created in front of the piston. A pneumatic pipe 25 extends forwardly from the pump to the top of a hollow thread collector 26 mounted on a fixed bracket 27. A thread holder designated generally at H is connected pneumatically to the interior of the thread collector and is the means by which the weft ends are kept taut and also the means by which a weft end of a transferred bobbin can be drawn into the thread collector 26 subsequent to cutting at the selvage.

Except as noted hereinafter, more particularly with reference to the vertical separator rods and the thread holder, the matter thus far described may be of common construction and formed as set forth in my prior Patent No. 2,199,353.

In carrying my present invention into effect I provide means associated with the vertical rods for effecting a considerable separation of the groups of weft ends, and also alter the thread holder in such manner that the separation provided at the magazine can be preserved at the intake mouth of the thread holder. Referring more particularly to Figs. 2, 3 and 4, each of the vertical rods 17 and 18 is provided with a pair of vertically extending wings or vanes serving as thread guides. Thus, rod 17 has front and back vanes 30 and 31, respectively, which are disposed as shown in Fig. 2 and have thread guide surfaces or edges 32 and 33, respectively, which are spaced apart a considerable distance. This distance may be equal at least to the spacing of the bobbins of the two front stacks as shown in Fig. 2. In similar manner, the rear rod 18 is provided with front and back wings 35 and 36, respectively, having vertically extending thread guiding edges 37 and 38. The wings of each vertical rod extend away from each other and preferably away from the associated thread slot, and the thread guide edges 32, 33, 37 and 38 serve as shown in Fig. 2 to space the groups of weft ends of the several stacks of bobbins.

The thread holder H is somewhat different from those heretofore proposed in that it is formed with an elongated horizontal intake mouth 40 facing the magazine and has an interior thread chamber 41 in which is located a vertical baffle 42 projecting in the present instance diagonally forwardly as set forth more particularly in Fig. 6. The rear part of the holder H is provided with an orifice 43 which communicates with the interior of the thread collector 26. A narrow front horizontally extending thread slot 44 in front wall 45 of the holder communicates with the upper part of the forward end of the intake mouth 40 and extends along the rear wall 46 of the holder H.

The groups W1—W4 of weft ends lead outwardly from the guide edges of their respective separators and extend into the elongated mouth 40 and converge toward the outer end of the baffle 42, after which they are drawn rearwardly through the orifice 43 toward or into the thread collector 26. These groups of weft ends are therefore separated from each other along the intake mouth, each group having its own zone, and when the bottom bobbin of any given stack is released for transfer its weft end will move downwardly from the associated group toward the bottom of the intake mouth 40 and will be detached not only from its own group but also from all the other groups leading into the intake mouth. Because of this relationship creation of subatmospheric pressures within the thread chamber 41 will draw

this weft end away from the loom and deposit it into the thread collector 26 at some later time in the operation of the loom subsequent to transfer, such as when the thread is cut at the selvage.

5 The lower ends of the thread guiding edges 32, 33, 37 and 38 are placed as indicated in Fig. 3 so that the lowest bobbin in a stack will have its weft end extending around the corresponding vertical guide edge, but when the bobbin moves 10 to transfer position its weft end will move below the associated guide edge and extend directly to the thread holder. It will be understood that magazines of the type set forth herein operate 15 with a bobbin releasing mechanism, such as the cradle 50, at the bottom of each stack of bobbins. The superposed bobbins in a stack rest on the corresponding cradle as they await transfer, and when a reserve bobbin is called from a selected stack in well-known manner the cradle thereof 20 will rock to permit the bottom bobbin of the stack to move down to the dotted line position shown in Fig. 3 where the tip end of the bobbin will be held by well-known supports one of which is shown at 51.

25 The bottom of each thread guiding edge terminates at a point between the weft end of the bobbin resting on the cradle and the weft end of a bobbin resting on the support 51. The pneumatic suction within the thread holder will tend 30 to draw the weft end of a bobbin in transfer position into mouth 40 and hold the thread taut, with the result that the weft end is not only moved downwardly in the intake mouth 40 but is also moved along the latter away from its group toward 35 a central position.

I find that the relation between the bottom of the thread guiding edges and the threads of the bobbins on the cradle and support 51 is of particular importance with respect to the front and 40 back stacks I and IV, but it also has the beneficial effect on the threads from the inner stacks II and III. An inspection of Fig. 2 will show that each group of weft ends is deflected from a straight line by the corresponding wing, and as each bobbin drops from the bottom of its stack to transfer position its thread will be straightened and caused to move with respect to the other threads of the corresponding group of weft ends.

From the foregoing it will be seen that I have 45 provided an improved thread holder and control mechanism for the weft ends of a reserve bobbin magazine so constructed that the weft ends approach an elongated intake mouth along separated paths. The separation of the paths is 50 effected by the fins on the vertical separators, and these fins terminate at their lower ends in such position that when the bottom bobbin of any stack moves to transfer position its weft end 55 will be straightened from its previously deflected or bent path and thereby be moved relatively to its group of weft ends. The baffle 42, the intake mouth 40, and the thread separators are so related 60 that the weft ends of the several groups of bobbins enter the intake mouth at different points distributed along its length and converge toward 65 the baffle 42. The combination of the magazine, thread holder and separator is not claimed herein 70 but is claimed in my copending application Serial No. 626,462, filed November 3, 1945, now Patent No. 2,427,538, September 16, 1947.

Having thus described my invention it will be seen that changes and modifications may be made therein by those skilled in the art without departing from the spirit and scope of the invention 75

and I do not wish to be limited to the details herein disclosed, but what I claim is:

1. A thread separator for a reserve bobbin magazine having a thread slot extending vertically therein, said separator having a central rod formed at the upper end thereof for attachment to the magazine and having a forwardly extending wing provided with a front thread guide edge and having also a rearwardly extending wing provided with a rear thread guide edge, said rod when attached at the upper end thereof to the magazine holding said guide edges substantially parallel to the thread slot.

2. A thread separator for a reserve bobbin magazine having a vertically extending thread slot, said separator comprising two vertically extending wings, one of said wings extending forwardly and having a front thread guide edge and the other wing extending rearwardly and having a rear thread guide edge, and said separator having means for attaching the same to the magazine with the front thread guide edge forward of the thread slot and with the rear thread guide edge rear of the thread slot.

3. In a reserve bobbin magazine provided with a pair of vertically extending stacks of reserve bobbins, the upper part of the magazine having a horizontally extending bobbin slot through which bobbins are passed for placement in said stacks, and the magazine having a vertically extending thread slot intermediate the stacks, a rod secured at the upper end thereof to the magazine above said bobbin slot and extending downwardly across the latter, and forwardly and backwardly extending thread guiding wings secured to said rod and extending substantially parallel to the thread slot and having their upper ends terminating below said horizontal bobbin slot.

4. In a magazine having a pair of vertical spaced stacks of reserve bobbins, one in front of the other, the magazine having a horizontally extending bobbin slot common to said stacks through which bobbins may be passed for placement in the stacks, the magazine also having a vertically extending thread slot intermediate the stacks, a rod secured to the magazine above the bobbin slot and extending downwardly across

said bobbin slot intermediate the ends thereof and substantially parallel to the thread slot, and thread guiding wings secured to said rod below the bobbin slot, one of said wings extending forwardly and having a thread guide edge forward of the thread slot and the other wing extending rearwardly and having a thread guide edge rearward of said thread slot.

5. In a magazine having a pair of vertical spaced stacks of reserve bobbins, one in front of the other, the magazine having a horizontally extending bobbin slot common to said stacks and having a vertical thread slot extending downwardly from the bobbin slot and through which extend the weft ends of the bobbins, a thread holder for weft ends, and a thread separator secured to the magazine and having a narrow upper part extending across the bobbin slot intermediate the stacks and having a wider lower part located between the magazine and the thread holder and providing front and back guide edges for the weft ends of the corresponding stacks.

6. A thread separator for a reserve bobbin magazine having a thread slot extending vertically therein, said separator having a rod formed at the upper end thereof for attachment to the magazine and a forwardly extending wing extending lengthwise of and secured to the rod and having a front thread guide edge the upper part of which is inclined upwardly and toward the rod and the lower part of which is substantially parallel to the rod, said rod when attached at the upper end thereof to the magazine holding said lower part of the guide edge substantially parallel to the thread slot.

RICHARD G. TURNER.
